FLUID TO FLUID HEAT EXCHANGER

Geoffrey Bertram Robert Feilden, Lincoln, and
Raymond Ernest Wigg, Ealing Common, London, England, assignors to Ruston & Hornsby Limited, Lincoln, England, a British company

Application April 10, 1950, Serial No. 155,032
In Great Britain April 14, 1949

7 Claims. (Cl. 257—236)

1

This invention relates to heat exchangers for transferring heat from one moving body of fluid to another, without admixture and preferably recuperatively by counterflow of the fluids in their respective passages. More particularly, the invention refers to tubular heat-exchangers in which one fluid is passed through a number of parallel tubes enclosed in a casing or casings through which the other fluid circulates in contact with the outer surfaces of the tubes.

The invention is applicable to heat-exchangers for incorporation in gas-turbine power-plants for utilising otherwise waste exhaust-heat to heat the compressed charge before combustion, thereby improving the thermal efficiency of the cycle. However, the improvements comprised in the present invention are not confined to this particular application but may find application in heat-exchangers for other purposes, nor are they confined to heat-exchangers in which both the fluids participating in the heat-transfer are gaseous, but may find application in heat-exchangers in which one or both of the fluids are liquid or in evaporators or condensers in which at least one of the fluids changes from the liquid to the vapour phase or vice versa.

In a large tubular heat-exchanger having a great number of tubes, acute problems are set by differential expansion effects and from this aspect large mono-bloc structures present great constructional difficulties. Such structures also present difficult problems in connection with assembly and maintenance—including cleaning, repair and replacement of components—and their size usually prohibits any possibility of rig-testing for checking performance.

The solution of these problems and others as may hereinafter be discussed forms the object of the present invention which makes use of a multi-bloc type of construction in which the individual tube-blocks are reduced to a manageable size, are mounted so that they can expand differentially without imposing stresses on their mountings or on each other and can each be easily removed and re-assembled without interference with the other tube blocks for cleaning, repair, testing or replacement. Reliable indications of the performance of the whole heat-exchanger can be obtained from rig-tests carried out on a single tube-block.

A tubular heat-exchanger according to this invention is primarily characterised by a number of independent parallel blocks of tubes, in each of which the tubes are fixed at each end in a header plate, that at one end being secured to a

2

collector member over an opening therein, the joint between the header plate and the collector member being fluid-tight, and that at the other end being provided with a funnel-shaped tubular extension or cowl, which is supported in an opening in another collector member by means of a fluid-tight expansion joint; and each block of tubes is encased for a considerable part of its length in a closely fitting casing leaving the tubes exposed at both ends, the fluid which circulates in contact with the outer surfaces of the tubes being compelled to pass through these tube-block casings by a bulkhead subdividing the interior of the external casing of the exchanger into two compartments and having openings receiving the tube-block casings, the joints between the bulkhead openings and tube-block casings being sealed in any convenient manner. The arrangement is such that one fluid is passed through the tubes from the collector having the sliding glands to the other in which the tube-blocks are located (or in the reverse direction), while the other fluid, admitted into the compartment of the outer casing on one side of the bulkhead, circulates through the spaces between the tubes within the casings of the individual tube-blocks in the opposite direction to that in which the first mentioned fluid circulates within the tubes and emerges into the compartment of the outer casing on the opposite side of the bulkhead, whence it is exhausted.

In a preferred embodiment of the invention the tube-blocks are disposed horizontally and the casings of each individual tube-block is provided with longitudinal horizontal flanges, preferably at the top, whereby the tube-block is supported on rollers, preferably located at or near each end of the tube-block casing and optionally at an intermediate point or points as well, the rollers being mounted on frames or bracket structures, secured to the outer casing of the exchanger or to the transverse bulkhead.

In a preferred form of construction the collector members are subdivided vertically, each branch being connected to a bank of vertically superposed tube-blocks, and the several collector branches being interconnected by an integral common header member at the top. Further, the casings of the individual tube-blocks are flanged near one end and these flanges abut on the margins of the openings in the bulkhead and carry stiffening brackets extending normally from the flanges and having holes through which studs projecting from the bulkhead pass to receive nuts by which the brackets and flanges are

clamped to the bulkhead to secure the block-casings thereto and provide an effective seal. These nuts are extended beyond the end of the studs to receive threaded tie-rods which pass through holes in lugs secured to the branches of the collector member at that end of the tube-block assembly to receive clamping nuts which carry the end loads on the collector member due to the internal fluid pressure in the tube-blocks. The tensile loads imposed on the tie-rods by the clamping nuts are transmitted back through the extended nuts and studs to the bulk-head, and are ultimately counteracted by the equal and opposite end loads, due to the internal fluid pressure, acting on the collector member at the other end of the tube-blocks, these last-mentioned end loads being transmitted back to the bulkhead through connections of the latter collector member to the outer casing, the tube-blocks themselves being connected to the last-mentioned collector member by expansion joints.

The compartment of the outer casing containing the inlet for the fluid which circulates round the outside of the tubes is made of large capacity to ensure low fluid velocity therein and even distribution of the fluid to the several tube-blocks and the bulkhead may be set back some distance beyond the entry ends of the tube-block casings from the end wall of this compartment.

The fluid inlet or outlet of each collector member is brought out through the wall of the outer casing through any convenient type of seal.

The tube-blocks are preferably of rectangular cross-section enabling them to be compactly arranged with small clearances between them; and are preferably similar, so that they are interchangeable.

Any one or more of the tube-blocks can be removed and replaced by removing the (detachable) end wall of the outer casing, the clamping nuts, tie-rods and extended nuts, and disconnecting the collector member and withdrawing it, thus enabling the tube-blocks to be slid out, and this is facilitated by the roller method of support. When a tube-block has been slid out a certain distance, a traveling slinging tackle suspended on a gantry extending longitudinally from a position next the detachable end wall of the outer casing and located above the level of the tube-blocks can be used to support the overhung end of the block while it is being further withdrawn, the slinging tackle comprising a yoke carrying a pair of rollers correctly spaced for slipping under the flanges of the tube-block casings.

It will be seen that each tube-block can expand lengthwise independently of the others, when the exchanger is in use, and that no racking strains are imposed on the collector members or the outer casing. Further, the fluid circulating outside the tubes is confined by the tube-block casings to paths in close contact with the tubes throughout the greater part of their length.

A further object of the invention is an improved form of flexible joint which may be used for the fluid-inlet connection of the outer casing of a heat-exchanger as described above.

In our improved flexible joint, the mating openings are provided with mutually facing metal flanges which are joined by a short flexible sleeve of asbestos-base fabric or like material clamped at its edges to the flanges by means of metal clamping strips. The asbestos may be rendered impermeable by any suitable treatment. The clamping strips may be secured by bolts passing through the flanges and the margins of the as-

10
15

bestos fabric sleeve, which may be made from a strip of the fabric with a sewn, stapled or riveted seam.

If the openings are rectangular or of any other shape having corners, a protective angle piece of sheet metal may be inserted at each corner between the fabric sleeve and the ends of the clamping strips, which may be bent outwards and bolted together.

A specific embodiment of the invention is illustrated in the accompanying drawings by way of example only and without implied limitations of the scope of the invention, which is defined in the appended claims.

In the drawings,

Figure 1 is a perspective view, partly broken away, of a heat-exchanger;

Figure 2 is a view of the same in side elevation partly broken away;

Figure 2a is a sectioned enlargement of the part of Figure 2 ringed with a dotted line;

Figure 3 is a view in end elevation of the intake collector member of the internal fluid-circulating system of the heat-exchanger;

Figure 4 is a plan view of the discharge collector assembly of the internal fluid-circulating system with the top wall removed;

Figure 5 is a detail view in end elevation of the flexible joint connecting the inlet opening of the heat-exchanger casing with an inlet trunk;

Figure 6 is a view in section on the line 6—6 of Figure 5;

Figure 7 is a view in section on the line 7—7 of Figure 6;

Figure 8 is a view in side elevation illustrating the arrangements for extracting the tube-blocks from the heat-exchanger.

The heat-exchanger comprises a generally rectangular outer casing 10 having an internal transverse bulkhead 11, in which are rectangular openings 12. The interior of the outer casing is thereby divided into two compartments, of which the smaller, lying to the right of the bulkhead in Figure 1, has a rectangular inlet opening 13 at the top, the left-hand end of the outer casing 10 (as seen in Figures 1 and 2) being open to an exhaust collector (not shown).

Within the outer casing are disposed a number of similar, rectangular-section tube-blocks 14, disposed longitudinally of the outer casing and closely spaced. Each tube-block comprises an open-ended rectangular casing 15, which passes through and fits closely into one of the openings 12 of the bulkhead and encases a bundle of closely spaced parallel tubes 16. The latter extend beyond the casing 15 and are exposed at both ends of the tube-block. The ends of the tubes 16 exposed in the compartment of the outer casing to the right of the bulkhead 11 in Figure 1 are secured in a header plate 17, the opposite ends of the tubes being secured in a header plate 18, the edges of which are secured in a tubular cowl 19. The fluid-conveying connections of the tube-blocks comprise an intake collector member 20 communicating with the cowls 19 and a discharge collector assembly comprising three tubular collectors 21 communicating with the tube-blocks 14 through the header plates 17.

The collectors 21 are disposed vertically and each communicates with a bank of vertically superposed tube-blocks. Each collector has a number of short branches 22 of rectangular cross-section corresponding in size and position to the tube-blocks and terminating in openings over which the header plates 17 fit. Each header plate 17 has a marginal flange 23, which fits over

70
75

the end of the corresponding branch 22, the joint being made fluid-tight by suitable packing, and is secured to the collector 21 by tie-bolts 24 which are inserted through apertured brackets 25 extending from the collector and carry clamps 26 engaging behind the marginal flange 23.

The discharge collector assembly also includes a header 27 comprising three elbows 28 secured to the collectors 21, two outlet pipes 29 forming continuations of the outer elbows 28 and branch pipes 30 connecting the central elbow 28 with the outlets 29, which are led out of the outer casing 10 through fluid-tight glands 31.

The intake collector member 20 comprises three vertical blind-ended tubes 32 having openings provided with skirts 33 which receive the open ends of the cowls 19 together with an integral header of double-yoke form comprising two intake elbows 34 having branches 35, 36, of which branches 35 communicate with the outer two collector tubes 32 and branches 36 with the central collector tube 32. Branches 35, 36 extend through a plate 37 which is welded to the branches all round the margins of the openings through which the branches pass; and this plate forms a detachable part of the top wall of the casing 10, being secured in any convenient way. The lower ends of the collector tubes 32 are provided with dowels 38 which are received in sockets 51 on the base of the outer casing 10. The collector member 20 is thus positively located by the plate 37 and dowels 38. The elbows 28 and 34 of the collector assembly 21, 27 and the collector member 20 are provided internally with flow-straightening cascades 57.

Expansion joints are provided between the cowls 19 of the tube-blocks 14 and the skirts 33 of the openings in the collector-tubes 32 of the collector member 20. The skirts 33 are cylindrical and the cowls 19 terminate in cylindrical portions 58, which fit slidably in the skirts 33 and are provided with circumferential grooves holding split spring sealing rings 59.

The upper wall of each tube-block casing 15 is extended laterally to form longitudinal horizontal flanges 39, which are accommodated in slots 40 formed in the bulkhead openings 12, and by which the tube-blocks 14 are supported on rollers 41 mounted on bracket structures 42 secured to the bulkhead 11 and to the inner faces of the walls of the outer casing 10.

The tube-block casings 15 also have collar-like flanges 43, which abut on the margins of the bulkhead openings 12, the joints being suitably packed to render them fluid-tight. The flanges 43 are stiffened by gusset plates 44 and carry stirrup brackets 45 extending normally to the plane of the flanges and away from the bulkhead 11. Studs 46 secured to the bulkhead extend through holes in the brackets 45 and carry clamping nuts 47 by which the tube-block casings 15 are secured to the bulkhead.

The nuts 47 are extended to receive threaded tie-rods 48 which pass through apertured lugs 49 extending from the collectors 21 and carry abutment nuts 50. Internal fluid pressure in the tube-blocks exerts forces on the collectors 21 tending to move them away from the bulkhead 11 and these forces are unresisted by the tubes 16 which are free to slide in the tube-block casings 15. The lugs 49, abutment nuts 50, ties 48, nuts 47 and studs 46 transmit these loads back to the bulkhead 11, while the corresponding forces on the collector tubes 32 of the collector member 20 at the opposite end of the heat-exchanger are

transmitted directly to the outer casing 10 by the plate 37 and dowels 38.

The end of the outer casing 10 enclosing the collector-assembly 21, 27 is constituted by a detachable cover 52, the joint indicated at 53 between which and the main body of the outer casing being formed by tongue and groove elements and the cover 52 being secured by tie-bolts 54 whose heads engage apertured lugs 55 extending inwardly from the wall of the main body of outer casing 10 and which carry external securing nuts 56.

Removal of the cover 52 gives access to the collectors 21 which are provided with detachable manhole covers 60 giving access to their insides for cleaning and like purposes. By undoing the joints between the collectors 21 and the header 27, removing the abutment nuts 50 and slackening off the tie-bolts 24 to release the clamps 26 from the marginal flanges 23 of the header plates 17 the collectors can be removed bodily. This gives access to the tube-blocks 14 which can be extracted singly by lengthwise sliding after unscrewing the clamping nuts 47 from the studs 46.

This operation is facilitated by the provision of an external gantry (see Figure 8) consisting of a bridge structure 61 supporting an I-joist 62, which extends longitudinally from the outer casing at a level above the tube-blocks and carries travelling slinging gear comprising a traveller 63 manually movable by means of a chain 64 and having a slinging hook 65, on which is slung a yoke 66 carrying a pair of rollers 67, spaced apart at the correct distance to be engaged under the flanges 39 of the tube-block 14 and take the weight of the latter as it is removed by endwise sliding from the support of the rollers 41 mounted in the outer casing 10.

The inlet opening 13 of the outer casing 10 communicates with a pair of inlet trunks 69 (Figure 2), the ends of which are flanged for connection to a flanged inlet plate 68 having two openings corresponding to the inlet trunks. Plate 68 is connected to the outer casing 10 by means of a flexible joint (see Figures 5 to 7). The margin of the plate 68 is of angle section and presents a flange 70 facing the margin of opening 13, while fixed to the outer casing 10 and surrounding the opening 13 is an angle section coaming 71, whose flange 72 faces and mates with the flange 70. A flexible sleeve 73 of graphited asbestos fabric (the seam of which (not shown) may be sewn or stapled) is slipped over the mating flanges 70, 72 and secured thereto by metal clamping strips 74 secured by bolts 75. At the corners the strips 74 are bent outwards and the adjacent bent ends are secured together by bolts 76, a metal angle piece 77 being inserted at each corner to hold the fabric sleeve against the flange 70 or 72.

The heat-exchanger described above is designed for incorporation in a stationary gas turbine for utilising exhaust heat to preheat the air leaving the compressor before entering the combustion chambers. Hot turbine-exhaust gas enters one compartment of the outer casing through opening 13, circulates through the tube-block casings 15 and is exhausted from the other compartment of the outer casing, and it will be seen that it cannot pass from one compartment to the other without passing through the tube-block casings in close contact with the tubes 16, through which air from the compressor, entering by way of the collector member 20, circulates in the opposite direction and is discharged through

the collector assembly 21, 27 to the combustion chambers, the heat-transfer being recuperative.

We claim:

1. A multi-block tubular heat-exchanger comprising an outer casing, a transverse bulkhead having openings therein and dividing the interior of the casing into two compartments, one compartment having an inlet opening and the other compartment having an outlet opening, a collector member in each compartment extending outside the casing for admission of fluid to one collector member and discharge of fluid from the other collector member, said collector members having openings therein, a number of closely spaced parallel tube-blocks, each comprising an open-ended tubular casing inserted through one of the openings of the bulkhead and secured to the bulkhead in a substantially fluid-tight manner, a bundle of closely spaced parallel tubes housed in said open-ended casing and extending beyond both open ends thereof, and a header plate secured to the tube ends at each end of the tube-block, one of said header plates being secured in a fluid-tight manner to the collector member in one compartment of the casing so as to register with an opening thereof, a tubular cowl-like extension of the other header plate registering with an opening of the other collector member, and a fluid-tight expansion joint between the cowl-like extension and the last-named collector member permitting movement of the cowl-like extension relatively to the collector member in the axial direction of the tube-block.

2. A tubular heat-exchanger as claimed in claim 1, in which each tube-block casing has horizontal, longitudinal flanges, and the outer casing includes internal bracket structures and rollers mounted thereon, said rollers supporting the tube-blocks by engagement with the undersides of the horizontal flanges thereof.

3. A tubular heat-exchanger as claimed in claim 1, in which the tube-block casings have external flanges abutting on the margins of the openings of the bulkhead and apertured bracket

structures extending normally from the flanges, and the bulkhead has studs extending therefrom through the apertures of the bracket structures, together with clamping nuts screwed on to the studs and engaging the bracket-structures for clamping the flanges to the bulkhead.

5 4. A tubular heat-exchanger as claimed in claim 3 including threaded tie-rods screwed into the clamping nuts, which are extended for this purpose, apertured lugs extending from the collector member on the same side of the bulkhead as the tie-rods, which extend through the apertures of the lugs, and abutment nuts screwed onto the tie-rods and engaging the lugs to resist the tendency of the internal pressure in the tube-blocks to move the collector member away from the bulkhead.

10 5. A form of construction of heat-exchanger as claimed in claim 1, in which there are at least two banks of vertically superposed tube-blocks and each collector member comprises at least two vertical branches and a common header element interconnecting the branches at the top.

15 6. A form of construction of heat-exchanger as claimed in claim 1 in which the tube-blocks are of rectangular cross-section.

20 7. A form of construction of heat-exchanger as claimed in claim 1, in which the several tube-blocks are similar and interchangeable.
